SKEIN WINDING MACHINE

William F. Twaddle, Manchester, N. H., assignor
to Amoskeag Manufacturing Company, trustees,
Manchester, N. H.

Application November 24, 1931, Serial No. 577,007

2 Claims. (Cl. 242—53)

This invention relates to an improved machine for winding yarns, and particularly rayon yarns, in skeins.

A common type of skein winding machine un-
5 winds the yarns from a multiplicity of spools or
packages and winds them on a reel in a corre-
sponding number of skeins. When the winding
is completed, the reel with its skeins is removed
from the machine and transferred to a stand
10 where the skeins are tied, leased, and removed
from the reel. The reel is subsequently returned
to the winding machine for the winding of other
skeins thereon. The removal of the reel on the
machine and its transference to a stand requires
15 considerable physical exertion and provides an
opportunity for the reel to become bruised and
damaged so that the yarn is liable to catch on
roughened or splintered surfaces of the reel and
thus become frayed and broken, especially when
20 the yarn is delicate, as with fine rayon yarn.
Furthermore, when a reel is out of the winding
machine, the machine is idle.

It is an object of the present invention to
provide an improved skein winding machine
25 wherein the reel is a permanent part of the ma-
chine and the skeins can be removed from the
reel without removing the reel from the machine.

It is a further object of the invention to provide
a skein winding machine having a plurality of
30 reels upon which the skeins are wound, leased and
tied, and from which the skeins can be removed
without removing the reels from the machine, the
arrangement being such that the reels are posi-
35 tioned successively into winding position and the
skeins can be wound, leased, tied and then re-
moved from one reel while the reel remains in the
machine and while yarn is being wound into skeins
on another reel.

Another object of the invention is the provision
40 of a skein winding machine wherein the winding
reel is supported at one end and the other end
is open and free from obstructions so that the
skeins can be withdrawn from the open unob-
45 structed end of the reel, the reel being collapsible
to facilitate the removal of the skeins.

A further object of the invention is the provi-
sion of a skein winding machine having a ro-
50 tatable support which carries a plurality of reels,
the reels being secured at one end only to the
support and the other end of the reels being
free and unobstructed so that the skeins can be
withdrawn therefrom.

Another object of the invention is the provision
55 of a skein winding machine having a plurality of
winding reels which can be moved successively

into and out of winding position and automatically
into and out of positive driving engagement
with reel-rotating mechanism which, when a reel
is in winding position, rotates it positively in
timed relation with the yarn-traversing mecha-
nism. 5

A further object of the invention is generally to
improve the construction and operation of skein
winding machines.

Fig. 1 is a plan view of the skein winding ma- 10
chine embodying the present invention.

Fig. 2 is a sectional view taken along line 2—2
of Fig. 1.

Fig. 3 is an enlarged sectional detail through
the winding reels taken along lines 3—3 of Fig. 1. 15

Fig. 4 is an enlarged detail of the locking mech-
anism for a collapsible bar of a reel.

Fig. 5 is a detail of the locking means for the
rotatable reel support.

As here shown, the skein winding machine em- 20
bodying the present invention comprises a sup-
porting frame 10 having a pair of end plates or
standards 12 in which the supporting shaft 14
of a rotatable reel support is journaled. Said
shaft at one end thereof is provided with a pair 25
of reel supporting members or frames 16 and 18
which are spaced apart on said shaft and have
corresponding arms 20 and 22 which extend in
opposite directions from said shaft.

A reel supporting shaft 24 is carried by and is 30
journaled in the ends of the corresponding arms
22 and a similar and parallel reel supporting shaft
26 is carried by and is journaled in the ends of
the corresponding arms 20. Said shafts project
beyond the frame member 16 in the same direc- 35
tion free from support and carry skein winding
reels 28 and 30 on the unsupported portions
thereof. The reels are or can be identical and
are collapsible so that the skeins on the reels can
be withdrawn over the open and unobstructed 40
left hand ends thereof.

Each reel comprises three yarn supporting bars
32 and a fourth similar bar 34, which bars are
parallel with their supporting shaft and are dis-
posed in equi-angularly spaced relation there-
about. The bars 32 are supported near the ends
thereof in radially-outstanding arms 36 of hubs
38 which are fixed to the reel supporting shaft.
The bar 34 is pivotally connected through yokes
40 fixed to the bar at its opposite ends, with the 50
outer ends of parallel sets of spaced links 42 and
44. The inner ends of said links are pivotally
connected to hubs 38 of the supporting shaft.
With this arrangement the bar 34 can be moved
in parallel lines inwardly toward the reel sup- 55

porting shaft from the position shown at the left hand end of Fig. 3 to the position shown in the right hand end of Fig. 3 for the purpose of reducing the peripheral extent of the reel and thereby allowing the skeins of yarn to become slack or loose on the reel so that they can be withdrawn from the unobstructed end of the reel. The bar 42 is locked in expanded position by a locking arm 46 which is pivoted to a hub 48 fixed to the reel supporting shaft and is extended between the pairs of links 42 where it is provided with a notch 50 that releasably engages a projection 52 of a bar yoke 40 and holds said bar against collapse. The locking arm 46 is urged in a locking direction by a spring 54 which bears outwardly against an ear 56 of said arm. Said arm is provided with a handle 58 at its free end which is accessible at the unobstructed end of the reel to permit the unlocking of the collapsible bar.

The rotatable support for the winding reels is adapted to be locked releasably in positions which correspond to the winding positions of the successive reels. For this purpose, the ends of the arms 20 and 22 of the rotatable supporting frame are provided with notches 60 each of which is adapted to be entered by the end of a locking bolt 62 carried by a bracket 64 of the stationary frame of the machine and urged toward the reel supporting frame by a spring 66. The locking bolt can be removed from holding engagement with the supporting frame by a lever 68, see Fig. 2, which is pivoted to the frame and is connected to the locking bolt by means of a pin 70. When the lever 68 is moved in a counterclockwise direction the locking bolt is withdrawn from one or the other of the notches 60 and the reel support then is free to be rotated to position another reel in winding position.

The reels are rotated when they are in winding position by a shaft 12, see Fig. 1, that is carried by one of the standards 12 and has a clutch connection with a driving pulley 74 that is loose on said shaft, the clutch connection including a clutch element 76 that is fixed to rotate with the shaft 12 and is axially movable thereon. When the clutch element is engaged with the rotating pulley 74, the shaft 12 is rotated. The shaft 12 has a driving gear 78 thereon and the reel support shafts 24 and 26 have similar gears 80 and 82 thereon, each of which is adapted automatically to be moved in turn into positive driving engagement with the gear 78 when its associated reel is brought into winding position.

The yarns are contained in spools or packages 84 which are supported by a shelf 86 at the bottom of the machine-frame and the yarns from the packages pass upwardly through suitable guides 90 and thence through loops 92 which are arranged in a more or less common manner to actuate the clutch element 76 and stop the operation of the machine if a strand of yarn breaks or runs out of the loop. From the loops, the strands pass through guides 94 in a horizontal bar 96 and thence upwardly to whichever one of the winding reels is in winding position. The bar 96 is reciprocated in more or less the usual manner in timed relation with the shaft 12 to guide the yarns onto the reel with proper traverse.

The usual treadle 98 is provided by which an operative watching the winding operation can actuate the clutch and start and stop the machine.

The manner of using the machine is substantially as follows:

When a sufficient amount of yarn has been wound in skeins on the reel 28, the winding operation is stopped, the locking bolt is removed from engagement with the reel support and the reel support is rotated 180° by hand to exchange the positions of the reels and to bring the empty reel 30 into winding position. This operation automatically disengages one reel from its positive driving connection with the operating shaft 12 and places the other reel in positive driving engagement therewith. The locking bolt is again engaged with the reel support to hold it in proper position and the yarns are severed from the reel 28 and are suitably connected to the reel 30. The machine is then set in operation to wind yarns in skeins on the reel 30. The operator leases and ties the skeins on the full reel and then collapses the reel by releasing the lock on the bar 34 and then removes the skeins from the unobstructed or left hand end of the reel, subsequently returning the bar 34 to its outward position and locking it in such position. The operation is repeated indefinitely. The shaft 14 is provided with guard plates 100 which are interposed between the two reels so as to protect the operator who is working on the skeins of the filled reel from coming in contact with the rotating reel, and to protect the ends on the reel being leased from snarling due to the wind set up by the other rotating winding reel. Said plates also serve to stiffen the shaft 14.

The machine thus described is capable of operating faster, without damage to the yarn, than the prior type of removable-reel machine. Since the reels are a permanent part of the machine, the parts can be heavier than heretofore and thus the reels can be rotated more rapidly than heretofore without setting up vibration that interferes with the proper winding of the yarn.

The reels are positively-driven when they are in winding position so that they are constrained to rotate in timed relation with the operation of the yarn-traverse mechanism, regardless of the speed of the reels. Consequently the yarn is laid on the reel in a definite accurate manner that facilitates the leasing of the skein and its subsequent unwinding whereas, with the removable reel, being friction-driven, the yarn could not be laid accurately, especially when the reel was rapidly rotated, due to slipping between the friction elements and the consequent haphazard and continually changing relation between the operations of the reel and the yarn-traversing mechanism.

I claim:

1. A machine for winding yarns into skeins comprising a rotatable supporting shaft, a frame carried by said shaft having pairs of oppositely extended arms, reel supporting shafts journaled at their one ends in corresponding arms of said frame and being free at their other ends, reels on which the yarns are wound into skeins carried by the free ends of said shafts, said frame being rotatable to exchange the position of said reels, means for releasably holding said frame in any one of its several positions, means including yarn-traversing mechanism for laying a plurality of yarns in separate positions disposed lengthwise of the reel that is in winding position for forming a plurality of skeins thereon, means for rotating said reels at a positive constant speed when they are in winding position including a constant-speed operating shaft having a driving

gear, said reel supporting shafts having gears which are movable automatically into and out of positive driving engagement with said operating shaft by the rotation of said supporting frame, 5 and means for collapsing the reels and permitting the removal of the skeins thereon over the unobstructed ends thereof.

2. A skein winding machine comprising a base having spaced upstanding end plates, a reel supporting frame including a horizontal pivot shaft extended between and journaled in said end plates, said shaft having a pair of horizontally spaced arms fixed thereon between said plates and near one of them, said arms being parallel 10 and extended both on both sides of the shaft, reel shafts parallel with and on opposite sides of said pivot shaft and journaled in and overhanging said arms, collapsible reels on said shafts, said pivot shaft with said reels being

capable of turning to exchange the position of said reels and said frame having provision for permitting such turning movement, releasable locking means engaging said reel supporting frame for locking the pivot shaft against turning with the reels in a horizontal plane, reel rotating means positioned to engage and rotate one only of said reels when they are successively positioned in the locked position of said pivot shaft so that one is rotated and the other is 15 idle, means for guiding yarns onto the reels to wind in skeins spaced lengthwise of the rotated reel, the end of the idle reel remote from said arms being clear of the adjacent end plate of said frame so that the end of the idle reel is 15 free and unobstructed and leased skeins on the idle reel can be removed endwise of the collapsed reel.

WILLIAM F. TWADDLE.
